UNITED STATES PATENT OFFICE.

GUSTAV OTTO, OF JERSEY CITY, NEW JERSEY, ASSIGNOR TO EDMUND T. OTTO, TRUSTEE, OF JERSEY CITY, NEW JERSEY.

DILATING-NOZZLE.

SPECIFICATION forming part of Letters Patent No. 728,175, dated May 12, 1903.

Application filed August 23, 1901. Serial No. 73,096. (No model.)

To all whom it may concern:

Be it known that I, GUSTAV OTTO, a citizen of the United States, residing at Jersey City, New Jersey, have invented certain new and useful Improvements in Dilating-Nozzles, of which the following is a specification, wherein reference is made to the accompanying drawings, forming part thereof.

My invention relates to dilating-nozzles; and the object of said invention is to provide a simple and efficient device which can be used either as a plain or dilating nozzle and which is capable of a variety of uses. Thus the device may be used as a vaginal, urethral, uterine, rectal, or phymosis dilator as well as a syringe-nozzle.

To these and other ends which will herein-after appear my invention consists in the novel arrangements and combination of parts to be hereinafter described and claimed.

In the accompanying drawings, Figure 1 is a side view of one form of device embodying my invention, the parts being shown in the contracted position. Fig. 2 is a like view of the same with the parts shown in the expanded position. Fig. 3 is a detail front or end view of the device. Fig. 4 is a detail face view of what I term the "expansion-plate."

The device comprises a tubular nozzle-section A, which terminates at one end in a nozzle a and at the opposite end with suitable means b for making connection with a rubber tube or other suitable means for supplying the nozzle. The nozzle a is preferably of bulbous form and constitutes a rose-nozzle. The nozzle-section A may be screw-threaded throughout a portion of its extent, as indicated at c, for coöperation with a suitable thumb-nut d. The thumb-nut d when employed is adapted to bear against one face of a collar e, which is freely movable on the nozzle-section. This collar e has rigidly secured thereto a plurality of spring dilating-arms f, each arm being preferably formed with a loop at the outer end, as indicated in the drawings. These arms f surround nozzle-section and are bent, as indicated at g, for purposes which will hereinafter appear. Secured to the nozzle-section in the rear of the bulbous nozzle is what I term an "expansion-plate" B. This expansion-plate may be per-

forated, as indicated at h, to permit a back-flow when the nozzle is in use, and guideways i are likewise provided for coöperation with the dilating-arms f. In the present instance these guides are in the nature of depressions in the periphery of the expansion-plate and an arm is adapted to slide in each depression, and the arms are in this manner prevented from being accidentally bent or deflected laterally from the position which they are intended to occupy. In other words, the arms are at all times maintained by the guides in the proper position one with relation to another, whether the arms be in the position indicated in Fig. 1 or in the position shown in Fig. 2 or in any of the intermediate positions. The curved portion g of each dilating-arm, bearing as it does against the edges of the plate B, will act as a cam, and when the thumb-nut d is screwed on nozzle-section A or the collar e is pushed forward the dilating-arms are moved from the position shown in Fig. 1 to that indicated in Fig. 2.

It will be observed that when the parts are in the position illustrated in Fig. 2 the inner face of the collar e will be brought into contact with a fixed sleeve j on the nozzle-section, which acts as a stop to limit further forward movement of the collar, and consequently prevent the dilating-arms from being expanded farther. It will likewise be seen that when the dilating-arms are contracted, as shown in Fig. 1, the nozzle-head is fully exposed, so that it may be used as an ordinary nozzle. When, however, the dilator is employed, the head of the nozzle will be withdrawn between the arms, where the openings in the nozzle are fully protected and are not liable to become clogged. It will also be observed that the rounded head of the nozzle presents an even surface with the dilating-arms when the parts are in the contracted position, so that but little obstruction is presented for the insertion of the device.

The thumb-nut d is particularly available where the instrument is employed as a rectal dilator or dilator-nozzle, because of the great pressure that is necessarily employed to expand the dilator. Furthermore, the nut prevents any chance of the dilator accidentally collapsing when in use.

By reason of the fact that the nozzle-head is forced forward to the exposed position when the dilator is contracted there is no opportunity afforded for the ends of the dilating-arms 5 to pinch or unduly compress the tender parts of the body when the instrument is in use.

The construction of the dilating-nozzle is such that it is adapted for a variety of uses. It may be used, for instance, as an ordinary 10 nozzle when the parts are in the position indicated in Fig. 1, and as a dilating-nozzle it may be used for the vagina, rectum, or urethra, and it may likewise be used as a phymosis dilator-nozzle, in which latter event it 15 may be advisable for better efficiency to slightly change the contour of the dilating-arms at the outer ends.

Having described my invention, what I claim, and desire to secure by Letters Patent, 20 is—

1. In a device of the character described, the combination of a nozzle-section, a movable collar thereon, a stop to limit the movement of the collar, spring dilating-arms carried by and rigidly secured to the collar and surrounding the nozzle-section, a perforated expansion-plate against which the dilating-arms bear and through the perforations in which the backflow may pass and mechanical 25 means for moving the collar to expand the arms, the head of the nozzle being contiguous to the ends of the arms when the arms are contracted.

2. In a device of the character described, 30 the combination of a nozzle-section, a movable collar thereon, spring dilating-arms carried by and rigidly secured to the collar and surrounding the nozzle-section, a perforated expansion-plate against which the dilating- 35 arms bear and through the perforations in which the backflow may pass, screw-threads on 40

the nozzle-section and a thumb-screw which coöperates with the threads on the nozzle-section and with the collar to move the latter in order to expand the dilating-arms.

3. In a device of the character described, the combination of a nozzle-section, a movable collar thereon, a stop to limit the movement of the collar, spring dilating-arms carried by and rigidly secured to the collar and surrounding the nozzle-section, a perforated expansion-plate against which the dilating-arms bear, guides which prevent an accidental lateral deflection of the dilating-arms, 50 screw-threads on the nozzle-section and a thumb-screw which coöperates with the threads on the nozzle-section and with the collar to move the latter in order to expand the dilating-arms.

4. In a device of the character described, the combination of a nozzle-section, a movable collar on the nozzle-section, a stop to limit the outward movement of the collar, spring dilating-arms carried by and rigidly secured to the collar and surrounding the nozzle-section, the head of the nozzle being projected forward beyond the ends of the arms and contiguous thereto when they are contracted, an expansion-plate having unobstructed openings therein through which the backflow may 55 pass and against which expansion-plate the dilating-arms bear, peripheral guides in the plate that prevent an accidental lateral deflection of the dilating-arms, screw-threads on the nozzle-section, and a thumb-screw 70 which coöperates with the threads on the nozzle-section and with the collar to move the latter in order to expand the dilating-arms.

GUSTAV OTTO.
